E. E. McANELLY.
 DRAWING BOARD.
 APPLICATION FILED NOV. 30, 1903.

UNITED STATES PATENT OFFICE.

ERNEST EUGENE McANELLY, OF DEVINE, TEXAS.

DRAWING-BOARD.

SPECIFICATION forming part of Letters Patent No. 783,973, dated February 28, 1905.

Application filed November 30, 1903. Serial No. 183,220.

To all whom it may concern:

Be it known that I, ERNEST EUGENE McANELLY, a citizen of the United States, residing at Devine, in the county of Medina and State of Texas, have invented a new and useful Drawing-Stand, of which the following is a specification.

My invention relates to drawing desks or stands, and has for its objects to produce a simple inexpensive device of this character which will be strong and durable and one which in practice will meet all the contingencies attendant upon storing the paper, instruments, boards, &c., or arranging the same for use and for maintaining the work at the proper inclination while being executed.

To these ends the invention comprises the novel features of invention and combination of parts more fully hereinafter described.

In the accompanying drawings, Figure 1 is a front elevation of a desk embodying the present invention. Fig. 2 is a vertical section from front to rear on the line 22 of Fig. 1 and showing the cover raised. Fig. 3 is a detail view.

Referring to the drawings, 1 designates the body of the desk, preferably of the form herein shown and consisting of side walls 2 and 3, a rear wall 4, a lower front wall 5, and a top or cover 6, pivoted at its front edge by hinges 7 or otherwise to the body, which latter is surrounded at its upper and lower ends by frames 8 9, which subserve the functions of strengthening and ornamenting the stand.

The lid or cover 6 is provided along its front edge with a rib or flange 10, against which a drawing-board may rest when the device is in use and the lid is tilted upwardly, in which latter position the same is adjustably sustained by a bar or member 11, pivoted at its upper end to the lid and having its lower end designed for engagement with teeth or steps 12, arranged in vertical spaced relation one above another and formed upon the outer edge of a bar or element 13, attached to and extending longitudinally of the inner face of rear wall 4. From this arrangement it will be seen that the cover may be adjusted to and supported at any desired inclination accord-

ing to the nature of the work under execution 50 and that when so inclined a drawing-board or the like resting upon the cover will be prevented from escaping by the rib or flange 10.

The desk is provided with a board-receiving compartment 14, open at its front and designed for the storage of drawing boards. This compartment has a bottom 15 mounted and sustained within the body of the stand, adjacent to the longitudinal center thereof, upon which bottom there is arranged a series 60 of upstanding ribs or flanges 16, disposed in parallel relation and constituting guides which receive between them the lower edges of the boards, the upper edges of the latter being engaged by depending studs or fingers 17, 65 formed upon the lower edge of a transverse connecting-board disposed at the upper end of the stand.

Beneath the compartment 14 and sustained upon suitable rails 18 is a sliding drawer 19, 70 designed to receive drawing-paper, &c., while above the compartment and beneath the lid 6 is a second drawer 20, sustained by guides 21 and adapted in practice to receive pens, ink, instruments, &c., this latter drawer being provided adjacent to its rear end with laterally-projecting pins or trunnions 22, which when the drawer is pulled outward engage behind the frame 8 to prevent the accidental escape 75 of the drawer and at the same time permit the same to assume a slight downward inclination, whereby its contents will move by gravity to a position at the front of the drawer for ready removal therefrom.

Pivoted to the outer face of the side wall 2, 80 adjacent to the top of the stand and within convenient reach of the front of the latter, is a leaf or shelf 23, designed in practice to receive and sustain instruments, &c., for convenient access while in use. This leaf, which is sustained in its operative position by a bar or member 24, pivoted at its upper end to the shelf and designed for the engagement of its lower end with a seat 25, formed in the wall of the stand, has an upstanding marginal flange 90 or rail 26 for preventing the accidental escape of articles from the shelf. The shelf is further provided at its outer longitudinal edge 95

with a triangular opening or socket 27, adapted to receive a measuring-scale and preferably formed by cutting a V-shaped groove in the edge of the leaf and closing the outer face of 5 the same by a plate or strip 28. Projecting from the opposite side wall 3 of the stand is a hook or member 29, adapted in practice to receive T-squares, triangles, &c., which when not in use may be suspended therefrom.

10 From the foregoing it is apparent that I produce a device which will afford every convenience and meet all of the contingencies which arise during the execution of drawings or the like and one which is designed and especially 15 adapted for use in manual-training schools, where the materials have to be stored at the end of each lesson. In attaining these ends it is to be understood that I do not wish to limit myself to the precise details herein set 20 forth, inasmuch as minor changes in the form, proportion, and exact manner of assemblage of the parts may be made without departing from the spirit of the invention.

Having thus described my invention, what I claim is—

25 The combination with a desk, of a pivoted cover therefor adapted to be adjusted at an inclination, guide-rails carried by the desk, a drawer supported by the rails and adapted for outward movement, and stop members carried by the drawer adjacent to its rear end and adapted for engagement with the front wall of the desk to limit the outward movement of the drawer, the rear portion of the drawer when drawn outward, being designed to bear 30 against the front portion of the cover to impart to the drawer a downward inclination coincident with that of the cover when adjusted.

35 In testimony that I claim the foregoing as my own I have hereto affixed my signature in 40 the presence of two witnesses.

ERNEST EUGENE McANELLY.

Witnesses:

JNO. T. BRISCOE,
WM. DRISCOL.
